UNITED STATES PATENT OFFICE

WILLIAM L. MORROW, OF STOCKTON, CALIFORNIA.

GAS-ENGINE.

No. 895,286.

Specification of Letters Patent.

Patented Aug. 4, 1908.

Application filed August 27, 1906. Serial No. 332,083.

To all whom it may concern:

Be it known that I, WILLIAM L. MORROW, a citizen of the United States, and a resident of the city of Stockton, county of San Joaquin, State of California, have invented certain new and useful Improvements in Gas-Engines; and I do declare the following to be a full, clear, and exact description of the same, such as will enable others skilled in the art to 10 which it appertains to make and use the same, reference being had to the accompanying drawings, and the characters of reference marked thereon, which form a part of this application.

15 My invention relates to improvements in gas engines and particularly to devices of this class known as "two-cylinder engines", and has for its object to improve the construction and to increase the efficiency and utility in 20 devices of this character. These objects I accomplish by a cylinder having a solid partition wall dividing said cylinder into two distinct chambers provided with an improved port mechanism and a separate compression 25 air chamber arranged thereabove, all as will appear by a perusal of the following specification and claims.

In the drawings similar characters of reference indicate corresponding parts in the several views.

30 Figure 1 is a side elevation of my improved engine. Fig. 2 is a longitudinal section of the said engine on the line $x-x$ of Fig. 1. Fig. 3 is a vertical section of the said 35 engine.

The improved engine comprises two cylinders 1-1' open at their outer ends and with the inner ends closed as at 4-4', the confronting faces of the closures each having a 40 half bearing to receive a shaft 25, the latter provided with cranks 26-27. The cylinders are supported upon a bed 28 and rising from the bed are standards 29-30 for supporting the shaft outside the cranks. The 45 outer ends of the cylinders are preferably reduced and provided respectively with oppositely-disposed guide-walls 2-2', while similar guide slots 3-3' are arranged in the upper sides of the reduced portions. The interiors of the cylinders form separate cylinders denoted respectively 5-6, and around the chamber portions of the cylinders water jackets 7-7' are arranged, as shown. Working in the chamber 5 is a piston 8 having a 50 rod 9 provided with a cross head 10 extending out through the slots 2', and 11 is a similar piston working in the chamber 6 and having a rod 12 provided with cross head 13 extending through the slots 2.

14 are driving rods secured to the cross heads 10 and 13 and connecting the same to cranks 26-27.

16 is a compressing air chamber communicating with the chambers 5 and 6 by means of ports 17, 17' and provided with heads 31 65 and 32. 18 is a piston working in said chamber 16 and provided with a rod 19 connected to the pistons 8 and 11 by means of vertical rods 20, 20' extending through the slots or guides 3, 3' and the rod 19 passing through 70 suitable stuffing boxes in the heads 31-32.

21 21 are open exhaust ports located in the sides of the cylinders 1' and leading from the chambers 5 and 6, said ports being a trifle nearer the closures 4-4' than are said 75 intake ports 17.

22 is a mixer pipe connected to the chamber 16 by means of intake check valves 23.

24 24' are the usual jump sparks connected into the chambers 5 and 6. 80

In using my improved engine the check valves 23 are regulated to permit a sufficient amount of explosive mixture to enter the compressing chamber 16. Then when the pistons 5 and 6 are operated the exhaust ports 21 are opened an instant before the intake ports 17 are uncovered thus allowing the exhaust of the gases. Then one of the intake ports 17 opens and the compression caused by the drive of the piston 18 causes 85 a charge to enter one of the chambers 5 or 6 as the case may be and the forward drive of the piston in said chamber compresses this charge near the closure 4-4' and the spark explodes said compressed mixture and 90 drives the said piston backward, and then the same operation takes place in the other chamber, the explosion always taking place on the half cycle of the engine, as is evident from the described construction of the engine. By this arrangement the explosive mixture is utilized to the fullest extent, and the compression in the chamber 16 is always exhausted against the pistons by reason of the connecting rods 19 and 20, and the compression in the chambers 5 and 6 tends to 100 equalize the compression in such chamber 16 and thus there is always a cushion brake on the said pistons when the spark is shut off, which causes the pistons to stop about the center of their respective chambers thus holding an explosion mixture in one of them ready. 105 110

to explode the instant the spark is connected, thus avoiding the necessity of "cranking" when it is desired to start the engine.

I have now entered into a detailed description of the present embodiment of my invention. Many small details of construction may be modified however within the scope of the appended claims without departing from the spirit of the invention.

Having thus described my invention I claim as new and useful and desire to secure by Letters Patent:

1. In a gas engine of the class described, two cylinders having exhaust ports leading therefrom, a shaft provided with cranks, an air chamber associated with said cylinders and with parts near its ends communicating with said cylinders slightly in advance of the exhaust ports of the same, pistons operating in said cylinders, connecting means between said pistons and cranks, a piston operating in said air chamber, connecting means between said air chamber piston and said cylinder pistons, and sparkers connected to said cylinders.

2. In a gas engine of the class described, two cylinders arranged end to end and with exhaust ports leading therefrom, a shaft mounted for rotation between said cylinders and provided with cranks, an air chamber associated with said cylinders and with ports near its ends communicating with said cylinders slightly in advance of the exhaust ports thereof, pistons operating in said cylinders, connecting means between said pistons and cranks, a piston operating in said air chamber, connecting means between said air chamber pistons and said cylinder pistons, and sparkers connected to said cylinders.

3. In a gas engine of the class described, two cylinders open at one end and closed at their other ends and arranged end to end with the closed ends in contact, said cylinders having exhaust ports and longitudinally-disposed guide slots, a shaft mounted for rotation between said cylinders and provided with cranks, an air chamber associated with said cylinders and with ports near its ends communicating with said cylinders slightly in advance of the exhaust ports thereof, pistons operating in said cylinders, cross-heads operating in said guide slots, piston rods between said cross-heads and the pistons of said cyl-

inders, driving rods between said cross-heads and cranks, a piston operating in said air chamber, connecting means between said air chamber piston and said cross-heads, and sparkers connected into said cylinders.

4. In a gas engine of the class described, two cylinders open at one end and closed at their other ends and arranged end to end with the closed ends in contact, said cylinders having exhaust ports and longitudinally-disposed guide slots, a shaft mounted for rotation between said cylinders and provided with cranks, an air chamber associated with said cylinders and with a port near its ends communicating with said cylinders slightly in advance of the exhaust ports thereof, pistons operating in said cylinders, cross-heads operating in said guide slots, piston rods between said cross-heads and the pistons of said cylinders, driving rods between said cross-heads and cranks, a piston rod connected to said air chamber piston and extending beyond the air chamber at each end, and connecting means between said air chamber piston rod and said cross-heads.

5. In a gas engine adapted to explode on the half cycle a main cylinder provided with a partition wall dividing the same into two distinct chambers, slots in the sides of such cylinder at each end thereof, pistons in said chambers, fly wheels journaled in said partition wall, suitable rods connecting said pistons to said fly wheels, and guided in said slots, slots in the top of said cylinder at each end thereof, a compression chamber arranged above said cylinder and connected to said chambers by intake ports, exhaust ports leading from said chambers at points a trifle nearer the partition wall than are said intake ports, a piston working in said compression chamber, rods connecting the said piston with the pistons in said chambers, said rods being guided in the said last named slots, and means for supplying the mixture to said compression chamber and means for cooling the said cylinder and its parts, all as set forth herein fully.

In testimony whereof I affix my signature in presence of two witnesses.

WILLIAM L. MORROW.
